UNITED STATES PATENT OFFICE.

JAMES T. MORGAN, OF WINSTED, CONNECTICUT, ASSIGNOR TO THE MORGAN SILVER PLATE COMPANY, OF SAME PLACE.

DESIGN FOR A CASKET-HANDLE.

SPECIFICATION forming part of Design No. 24,484, dated July 16, 1895.

Application filed June 20, 1895. Serial No. 553,473. Term of patent 7 years.

To all whom it may concern:

Be it known that I, JAMES T. MORGAN, of Winsted, in the county of Litchfield and State of Connecticut, have invented a certain new and useful Design for Casket-Handles; and I do hereby declare the following to be a full, clear, and exact description of the invention, such as will enable others skilled in the art to which it pertains to make and use it, reference being had to the accompanying drawing, which forms part of this specification.

My invention has relation to designs for casket-handles, and which is fully shown in the accompanying drawing.

The leading feature of my design consists of a rope pattern or style, in which the plates A have the rope pattern B at their edges and

the handle or bar portion C, likewise of rope pattern. The ends of the bar or handle proper C are provided with the turban knots 20 D, and the upper ends of the portion G of the handle made U-shaped, as shown, and of the rope pattern.

Having thus fully described my invention, what I claim, and desire to secure by Letters 25 Patent, is—

The design for a casket handle substantially as herein shown and described.

In testimony whereof I affix my signature in presence of two witnesses.

JAMES T. MORGAN.

Witnesses:

STEPHEN C. WHEELER,
JAMES P. GLYNN.
